MINOT F. FOLLANSBEE, OF WHITMAN, MASSACHUSETTS, ASSIGNOR TO UNITED SHOE MACHINERY COMPANY, OF PATERSON, NEW JERSEY, A CORPORATION OF NEW JERSEY.

HEEL-ATTACHING MACHINE.

1,030,577.

Specification of Letters Patent. Patented June 25, 1912.

Application filed January 2, 1907, Serial No. 350,393. Renewed January 30, 1912. Serial No. 674,379.

To all whom it may concern:

Be it known that I, MINOT F. FOLLANSBEE, a citizen of the United States, residing at Whitman, in the county of Plymouth and 5 Commonwealth of Massachusetts, have invented certain Improvements in Heel-Attaching Machines, of which the following description, in connection with the accompanying drawings, is a specification, like 10 reference characters on the drawings indicating like parts in the several figures.

This invention relates to heel attaching machines and more particularly to heel attaching machines having provision for 15 curing top lifts to heels.

In the use of machines for blind-nailing heels to shoes, it is a common practice to apply an adhesive material to a top lift prior to the spanking operation to insure 20 a close joint between the top lift and the face of the heel and to secure the lift firmly to the heel. In practice, the adhesive material is manually applied, and it is the primary object of the present invention to 25 provide means whereby this operation may be mechanically performed. The adhesive material to be applied will be hereinafter referred to as "cement" but it will be understood that this term in generically used to 30 cover any kind of adhesive material desired to be used.

The present embodiment of the invention is shown applied to a machine having a top lift carrier arranged for movement from 35 an inoperative position in which it is manually supplied with a lift, to an attaching position in which the lift is spanked upon a previously attached heel. In order that cement-applying mechanism for a machine 40 of this type shall possess simplicity in construction and accuracy and reliability in operation, it is desirable that the cement be applied to a top lift after it has been inserted in the carrier and while the carrier is in a stationary, inoperative position. The arrangement herein disclosed is such that the application of cement to a top lift is 45 directly controlled by the operator, so that after he has inserted a lift by hand in the carrier he may bring a cementing device into operation, independently of the actuation of the carrier. According to the construction shown, a movable cement-carrying device is arranged normally out of opera- 50 tive relation to the top lift carrier and is

adapted for movement in a path suitable to bring its acting surface into engagement with a top lift held upon the carrier in the inoperative position of the latter, the actuation of said device being effected at the 60 will of the operator.

It is desirable that the amount of cement applied to top lifts be capable of being controlled. The application of an excessive amount is not only wasteful but is also disadvantageous in that the excess is liable to reach parts of the shoe or of the machine where its presence would be obnoxious. An important feature of the present invention, accordingly, comprises means whereby the 70 amount of cement applied to top lifts may be controlled. According to the present arrangement, the area of contact between the cement-carrying device and the top lift may be varied so that cement may be applied to 75 a greater or less portion of the face of the lift as may be desired. The cement is preferably applied to only a part of the face of a lift, near its center, since the pressure with which the top lift is forced upon the 80 heel is sufficient to spread the cement into a thin film covering substantially the entire face of the lift.

In the particular embodiment of the invention illustrated, the top lift carrier is arranged for movement in a horizontal plane, and the construction of the heel attaching machine is such that the top lift supported by the carrier is required to be sustained with its tread face uppermost. Beneath 90 and in line with the top lift carrier in its receiving position, and adjacent thereto, is provided a cement receptacle. An oscillatory cement-carrying device is arranged for movement about a horizontal axis between 95 the receptacle and the carrier. Means are provided for holding the device in a lower position, in which it is out of contact with the top lift, and provision is made for swinging the device into engagement with 100 the under face of the top lift by means of suitable mechanism adapted to be actuated by the operator.

The cement-carrying device herein shown is provided with a cylindrically curved cement-carrying surface, and is arranged for oscillatory movement about an axis parallel to the axis of said surface. Preferably the surface of the device is formed of yielding material and is of progressively increas- 110

ing radius in a direction opposite to the acting movement of the device. The provision of a surface of increasing radius renders the application of cement to a lift independent of its thickness, and the yielding nature of said surface causes the area of contact with the lift to be determined by the extent to which said surface is flattened in its engagement with the lift. Preferably the material forming said surface is also of an absorbent character, as the use of such material is of advantage in securing a uniform action of the cement-applying device.

The arrangement of the parts may be such that the upward movement of the cement-carrying device is limited by its engagement with the face of the lift, but said movement is preferably positively limited by other means. I have shown an adjustable stop arranged to arrest said movement of the device and limit the pressure of engagement of the yielding surface of the device with the lift, this mechanism affording means whereby the amount of cement applied to the lifts may be limited, and permitting variation in the area covered with cement.

Other features of the invention will be hereinafter described and defined in the claims.

In the drawings which illustrate mechanism constituting one embodiment of the invention, Figure 1 is a view in plan of a portion of a heel attaching machine with said mechanism applied thereto; Fig. 2 is a perspective view of the cement-applying device and its actuating mechanism; Fig. 3 is a view in elevation of a portion of the mechanism shown in Fig. 1, illustrating the operation of the cement-applying device.

Referring to the drawings, in Fig. 1 the reference numeral 1 indicates a rotatable carrier having spring-pressed heel clamps and top lift clamps. This carrier is the same in construction as that illustrated in U. S. Letters Patent 446885, to J. H. Pope, dated February 24, 1891, the present embodiment of the invention being herein described, for purposes of illustration, as applied to a machine of the construction shown in said patent. It will be understood that the carrier 1 is arranged for swinging movement about a pivot 2 and that a top lift is inserted between the spring-pressed clamps 4 when the carrier is in the position shown in Fig. 1. After the attachment of a heel, the carrier is moved by the operator through an angle of 90 degrees to bring the top lift clamps into the position previously occupied by the heel clamps, and the securing of the top lift is effected by forcing said lift upon the ends of the nails of the attached heel. A spanker plate 6 constitutes an abutment for the tread face of the top lift in the spanking operation. Beneath the rotatable carrier is provided a table 8 upon which is supported

cement-applying mechanism. A cement receptacle 10 is arranged beneath and in line with the top lift carrier in its receiving position, and between said receptacle and the carrier is journaled a horizontal shaft 12 arranged at right angles to the length of the top lift. To the shaft 12 is secured a segmental shaped member 14 which is provided upon its curved face with a layer of felt 16, as shown upon the drawings. The arrangement of the member 14 and felt 16 with relation to the shaft 12 is preferably such that the distance between the shaft and the surface of the felt increases in a direction opposite to the arrow shown in Fig. 3. The member 14 and the felt 16 are so arranged as to cause the curved surface of the cement-applying device to be of a cylindrical contour, parallel to the axis of the shaft 12. Upon the rear end of the shaft 12 is provided a drum 18 provided with two grooves upon its periphery. In one of the grooves a cord 20 is arranged and secured to the drum, said cord coöperating with a spring 22 to hold the cement-carrying device yielding in approximately the position shown in full lines in Fig. 3. A cord 24 is secured to the drum in the other groove and is arranged to effect movement of the cement-carrying device into engagement with the top lift, said cord being connected to a treadle 26 to permit its convenient actuation at the will of the operator. To limit the movement of the cement-carrying device into engagement with the top lift, a pin 28 is arranged upon the drum 18 in position to engage a fixed portion of the machine at a predetermined point in the movement of the cement-carrying device. As shown, the drum 18 is provided with a series of holes adjacent to its periphery, permitting the pin 28 to be adjusted in position to vary the limit of movement. As will be obvious from Fig. 2, said pin in the movement of the drum 18 engages the bracket adjacent to said drum and arrests the movement of the cement-carrying device.

In the operation of the mechanism shown, the carrier 1 being in the position shown in Fig. 1, the operator or his attendant inserts a top lift by hand between the clamps 4. It will be observed from Fig. 3 that when the cement-carrying device is in its lower inoperative position, space above it is afforded for the convenient insertion of the top lift in the carrier. After the insertion of the lift and while the carrier remains in its stationary inoperative position, the treadle 26 is depressed and the cement-carrying felt 16 swung into engagement with the lower face of the lift. It will be seen that on account of the gradually increasing radius of the curved surface of the felt, said surface in its movement assumes a position in which the face of the lift is tangent thereto; for

example, the dotted line position shown in Fig. 3. Further movement of the device compresses and somewhat flattens the felt and causes cement to be spread over an area of the top lift of an appreciable extent, preferably of slightly greater length than the width of the felt. The application of cement to a top lift is rendered independent of the thickness of the lift, since variation in thickness merely causes a different portion of the curved surface of the felt to be brought in contact with the face of the lift. The return of the cement-carrying device to its inoperative position is effected by releasing the treadle, and the movement of the top lift into attaching position is secured by turning the carrier by hand into position above the shoe.

It will be seen that the amount of cement applied to a top lift is dependent upon the pressure with which the cement-carrying device is brought into engagement with the face of a top lift, since an increase in the compression of the absorbent felt causes an increase in the amount of cement forced from the felt upon the lift, and also increases the area of contact between the device and the lift. The amount of cement applied to top lifts may thus be changed by varying the pressure of engagement of the device with the lifts. I have shown means for limiting the pressure of engagement between the cementing device and a top lift, but it will be obvious that said pressure might be controlled by applying more or less pressure to the treadle, dispensing with said means. I prefer however to employ means for positively limiting the area covered with cement.

40 It will be seen that the pin 28 limits the movement of the cement-carrying device into engagement with a top lift, and that by changing the position of this pin upon the drum 18 this limit may be varied. Since the area of contact between the device and the face of the lift is dependent upon the extent of upward movement of the device, this feature permits the area covered with cement by said device to be varied. Occasion for variation in this area may arise where considerable change is made in the size of top lifts being attached. Adjustment of the pin 28 may also be advantageous where the level of cement in the cement receptacle is near either its upper or lower limit. It will be obvious that other mechanical devices may be employed for arresting the movement of the cement-applying device.

The mechanism shown on the drawings is adapted to secure the application of cement to a lift without displacing it upon its carrier, and moreover the cement-carrying device is brought into firm and even engagement with the face of the lift so that distribution of the cement over a predetermined

area is insured. It will be seen that the movement of the cement-carrying device is in a path such that at the point of first contact the acting part of the device is moving nearly parallel with the face of the lift and further contact of the device with the lift is effected while said device is being given a certain amount of movement. The arrangement of the parts is also such that the movement of the device toward the lift does not disturb to any considerable extent the contents of the cement receptacle. Since successive portions of the felt surface enter the cement in the oscillation of the device, the application of cement to substantially all parts of said surface is insured. Moreover on account of the absorbent nature of the felt distribution of cement over the entire area of said surface is insured by capillary action.

Having thus described my invention, what I claim as new and desire to secure by Letters Patent of the United States is,—

1. A heel attaching machine, having in combination, means for sustaining a heel lift in stationary position, a movable cement carrying device for applying cement to the lift while held in said position, and means manipulated by the operator for moving said device into contact with the lift and thereafter along the face of the lift.

2. A heel attaching machine, having in combination, a carrier for heel lifts arranged for movement from a receiving position into an attaching position, a movable cement carrying device for applying cement to a lift sustained by the carrier and means manipulated by the operator for moving said device into contact with the lift and thereafter along the face of the lift, said means being arranged to be actuated independently of the carrier.

3. A heel attaching machine, having, in combination, means for sustaining a heel lift in stationary position, a cement carrying device for applying cement to a predetermined part of the lift while held in said position and means permitting the area of contact of said device with the lift to be varied.

4. A heel attaching machine, having, in combination, means for sustaining a heel lift, a cement carrying device for applying cement to the central part of the lift and means for varying the area of contact of said device with the lift.

5. A heel attaching machine, having in combination, a carrier for heel lifts, a cement receptacle, an oscillatory cement-applying device between said carrier and receptacle, having a cylindrically curved, cement-carrying surface and arranged for movement about an axis parallel to the axis of said surface, and vertically below a lift sustained by the carrier, and means for moving said device from the receptacle into

engagement with said lift and thereafter along the face of the lift.

6. A heel attaching machine, having in combination, a carrier, a cement receptacle, 5 an oscillatory cement-applying device between said carrier and receptacle, arranged for movement from said receptacle into engagement with a lift sustained by the carrier, said device having a curved cement- 10 carrying surface of progressively increasing radius and means for oscillating said device.

7. A heel attaching machine having in combination, means for sustaining a heel 15 lift, a cement receptacle, a cement-applying device arranged for movement from said receptacle into engagement with the face of the lift about a fixed axis between the heel lift and the receptacle, said device having a 20 curved yielding cement-carrying surface of progressively increasing radius, and means for actuating said device.

8. A heel attaching machine, having, in combination, means for sustaining a heel 25 lift in stationary position, a cement-applying device having a cement-carrying surface formed of yielding, absorbent material, means arranged to be actuated by the operator for bringing said surface of the device 30 into engagement with the lift, and means for limiting the pressure of engagement of said surface with the lift.

9. A heel attaching machine, having in combination, a carrier for heel lifts arranged for movement in a horizontal plane 35 and restrained from vertical movement during the cementing operation, a cement receptacle arranged beneath and in line with said carrier in its receiving position, an oscillatory cement-applying device having a cylindrically curved cement-carrying surface arranged for engagement with the lower face of the lift, means for swinging said device from contact with cement in 40 the receptacle into engagement with the lift and thereafter along the face of the lift and means for returning said device to its inoperative position.

10. A heel attaching machine, having in 50 combination, a carrier for heel lifts arranged for movement in a horizontal plane and restrained from vertical movement, a cement receptacle arranged beneath and in line with said carrier in its receiving position, an oscillatory cement-applying device 55 arranged for movement about a horizontal axis and having a cylindrically curved yielding cement-carrying surface arranged for engagement with the lower face of the lift and means for actuating said device independently of the movement of the carrier.

11. A heel attaching machine, having in 60 combination, a carrier for heel lifts arranged for horizontal movement from a receiving position into an attaching position

and restrained from vertical movement, a cement-carrying device arranged normally out of operative relation to said carrier, and means for moving said device into engagement with a lift sustained by the carrier 70 and thereafter along the face of the lift arranged to be actuated at the will of the operator independently of the actuation of the carrier.

12. A heel attaching machine, having in 75 combination, a heel lift carrier arranged for movement in a horizontal plane and adapted to sustain a lift with its tread face uppermost, a cement receptacle arranged beneath and in line with the carrier in its receiving 80 position, a cement-applying device having a curved cement-carrying portion formed of yielding absorbent material for transferring cement from said receptacle to the lower face of the lift, said device being arranged 85 for movement about a horizontal axis between the receptacle and the carrier in line with the lift, means for holding said device yieldingly out of operative relation to the lift, and means for moving said device into 90 engagement with the lift arranged to be actuated at the will of the operator.

13. A heel attaching machine, having in combination, a heel lift carrier arranged to sustain a lift with its tread face uppermost, 95 a cement receptacle arranged beneath the carrier, a cement-applying device having a curved cement-carrying portion formed of yielding absorbent material for transferring cement from the receptacle to the lift, said 100 device being arranged for movement about a horizontal axis between the receptacle and the carrier, means for moving said device into engagement with the lift arranged to be actuated by the operator, and means for 105 limiting the pressure of engagement of said device with the lift whereby the amount of cement applied to the lift may be controlled.

14. A heel attaching machine having, in combination, a heel lift carrier movable in 110 an arc from receiving to attaching position, a cement receptacle, a cement applying device arranged for movement about an axis parallel with the surface of the lift to be cemented from the receptacle into engagement 115 with the lift, a spring acting normally to maintain the cement applying device away from the carrier so that a lift may be introduced into the carrier, and means whereby the cement applying device may be moved 120 by the operator independently of the carrier and in opposition to the spring to coat a portion of the lift before the carrier is moved out of receiving position.

15. A heel attaching machine having, in 125 combination, a heel lift carrier movable in a horizontal path from cementing position to attaching position, a cement receptacle located below the carrier, a cement applying device movable about an axis parallel with 130

the face of the lift to be coated, a spring for swinging the applying device away from the carrier, and a treadle connected with said device and so arranged that its operation acts to swing the cement applying device into engagement with the lift independently of the movement of the carrier and while the carrier is positioned in its horizontal path.

10 16. A heel attaching machine having, in combination, a carrier for heel lifts arranged for movement in a horizontal plane to and from position over a shoe and restrained from vertical movement during the 15 cement applying operation, a cement receptacle arranged beneath and in line with the carrier when in a position remote from the shoe, a cement applying device for transferring cement from said receptacle to a lift on the carrier, means for holding said device away from the carrier and dipping into the cement, and manually controlled means for moving said cement applying device into engagement with the lift 20 on the carrier at the will of the operator.

25 17. A heel attaching machine having, in

combination, a carrier for heel lifts arranged for movement in a horizontal plane to and from position over a shoe, a cement receptacle arranged beneath and in line with the carrier when in a position remote from the shoe, a cement applying device having a curved cement carrying face formed of yielding absorbent material for transferring cement from said receptacle to a lift on the 30 carrier, means for holding said device away from the carrier and with a portion of its curved cement carrying face dipping into the cement, and manually controlled means for moving said device to bring its cement 35 carrying face into engagement with the lift on the carrier at the will of the operator, the amount of pressure of said device on the lift being limited.

In testimony whereof I have signed my 40 name to this specification in the presence of two subscribing witnesses.
